CERTAIN THIOLCARBAMATES AND USE
AS HERBICIDES

Harry Tilles, El Cerrito, and Joe Antognini, Mountain View, Calif., assignors to Stauffer Chemical Company, a corporation of Delaware

No Drawing. Application January 17, 1956
Serial No. 559,541

13 Claims. (Cl. 71—2.7)

This invention relates to certain novel compositions of matter, the method of making the compositions, and the use of such compositions as herbicides. More particularly, it has been found that certain alkyl N,N-dialkylthiolkarbamates have valuable herbicidal properties and are particularly useful as pre-emergence herbicides.

The following is a representative list of compounds which have been found useful (for convenience, code numbers have been assigned to the compounds and are used hereinafter):

Code	Name
R-1608	Ethyl N,N-di-n-propylthiolkarbamate.
R-1606	Methyl N,N-di-n-propylthiolkarbamate.
R-1607	n-Propyl N,N-di-n-propylthiolkarbamate.
R-1817	Ethyl N,N-pentamethylethiolkarbamate.
R-1819	n-Propyl N,N-pentamethylethiolkarbamate.
R-1854	Isobutyl N,N-di-n-propylthiolkarbamate.
R-1857	n-Butyl N,N-di-n-propylthiolkarbamate.
R-1866	Methyl N,N-di-n-butylthiolkarbamate.
R-1870	Ethyl N,N-di-n-butylthiolkarbamate.
R-1891	sec-Butyl N,N-di-n-propylthiolkarbamate.
R-1899	n-Amyl N,N-di-n-propylthiolkarbamate.
R-1903	n-Propyl N,N-di-isopropylthiolkarbamate.
R-1906	n-Butyl N,N-di-isopropylthiolkarbamate.
R-1893	sec-Butyl N,N-di-isopropylthiolkarbamate.
R-1905	n-Amyl N,N-di-isopropylthiolkarbamate.
R-1880	n-Propyl N,N-di-n-butylthiolkarbamate.
R-1908	Methyl N,N-di-isobutylthiolkarbamate.
R-1910	Ethyl N,N-di-isobutylthiolkarbamate.
R-1912	n-Propyl N,N-di-isobutylthiolkarbamate.
R-1913	Isopropyl N,N-di-isobutylthiolkarbamate.

Thus, the compounds of the present invention may be represented by the formula:

wherein R₁ is a lower alkyl radical and, R₂ and R₃ are lower alkyl groups which have at least three carbon atoms. R₂ and R₃ may be a single alkyl group having at least five carbon atoms and having two bonds available for attachment to the nitrogen atom, as in R-1817 wherein N forms a part of a ring structure.

The following illustrative examples demonstrate the methods which may be employed to make typical compounds of the present invention. In the examples, all parts are by weight.

Example I (R-1608).—Sodium is dispersed in xylene using oleic acid as the stabilizing agent until a particle size of 5–200 microns in diameter is obtained. Dispersion, equivalent to an amount of 16.9 parts (0.733 mole) of sodium, is then transferred to a reactor which has been previously flushed out with argon (or other inert gas such as nitrogen). A solution of 50 parts (0.806 mole) of ethanethiol dissolved in 86 parts of xylene is then gradually added to the sodium dispersion over an interval

2

of 30 minutes. The temperature is maintained at 25° to 36° C. by cooling. The sodium ethylmercaptide forms as finely divided crystals which make an easily stirrable slurry. This suspension is heated to reflux, the heat is turned off, and 120 parts (0.733 mole) of di-n-propylcarbamyl chloride is added over an interval of 17 minutes to the refluxing slurry. The heat of reaction is sufficient to keep the xylene refluxing. After all of the di-n-propylcarbamyl chloride has been added, the mixture is refluxed for an additional 3 hours. It is then cooled, filtered from sodium chloride which has formed during the reaction, and the solvent is removed under reduced pressure. The residual liquid is then distilled under vacuum to give 125.5 parts (90.6% yield) of ethyl N,N-di-n-propylthiolkarbamate (B.P. (31.5 mm.) 135.5° C.—137.0° C., n_D^{27} 1.4770). The following analysis is obtained:

	Calculated for C ₆ H ₁₀ NOS	Found
Percent C.....	57.1	57.41
Percent H.....	10.1	10.26
Percent N.....	7.4	7.17
Percent S.....	16.9	16.71
Molecular weight.....	189	185

Example II (R-1607).—When the general procedure of Example I is repeated except that 38 parts (0.50 mole) of 1-propanethiol, sodium dispersion equivalent to 9.2 parts (.40 mole) of sodium, and 65.5 parts (0.40 mole) of di-n-propylcarbamyl chloride are employed, there is obtained 70.3 parts (86.5% yield) of n-propyl N,N-di-n-propylthiolkarbamate (B.P. (30 mm.) 149–150° C., n_D^{27} 1.4750). The following analysis is obtained:

	Calculated for C ₁₀ H ₂₁ NOS	Found
Percent C.....	59.1	59.22
Percent H.....	10.3	10.41
Percent N.....	6.9	7.01
Percent S.....	15.8	15.77

Example III (R-1880).—When the general procedure of Example I is repeated except that 9.12 parts (0.12 mole) of 1-propanethiol, sodium dispersion equivalent to 2.3 parts (0.10 mole) of sodium, and 19.2 parts (0.10 mole) of di-n-butylcarbamyl chloride are employed, there is obtained 20.4 parts (88.3% yield) of n-propyl N,N-di-n-butylthiolkarbamate, (B.P. (15 mm.) 156.5–159° C., n_D^{27} 1.4742).

Example IV (R-1854).—When the general procedure of Example I is repeated except that 16.9 parts (0.188 mole) of 2-methyl-1-propanethiol, sodium dispersion equivalent to 3.45 parts (0.15 mole) of sodium and 24.5 parts (0.15 mole) of di-n-propylcarbamyl chloride are employed, there is obtained 25.2 parts (77.3% yield) of isobutyl N,N-di-n-propylthiolkarbamate (B.P. (18 mm.) 143–145° C., n_D^{24} 1.4744).

Example V (R-1857).—When the general procedure of Example I is repeated except that 16.9 parts (0.188 mole) of 1-butanethiol, sodium dispersion equivalent to 3.45 parts (0.15 mole) sodium and 24.5 parts (0.15 mole) of di-n-propylcarbamyl chloride are employed, there is obtained 24.8 parts (76% yield) of n-butyl N,N-di-n-propyl-

thiocarbamate (B.P. (19 mm.) 151.0-151.5° C., $n_D^{24.5}$ 1.4766).

Example VI (R-1866).—The general procedure of Example I was followed except that 25 parts (0.52 mole) of methanethiol is added in small portions at 50-60° C. to the sodium dispersion equivalent to 2.3 parts (0.10 mole) of sodium. It is necessary to make sure that unreacted mercaptan does not build up in the reaction mixture since a violent reaction may take place if too much unreacted mercaptan is present with unreacted dispersion. After all of the sodium dispersion has reacted which is evidenced by the reaction mixture changing from a purplish hue to a white color, it is heated to reflux and 19.2 parts (0.10 mole) of di-n-butylcarbamyl chloride is added. After working up in the usual manner, there is obtained 13.9 parts (68.5% yield) of methyl N,N-di-n-butylthiocarbamate (B.P. (20 mm.) 144-146° C., $n_D^{30.5}$ 1.4760).

Example VII (R-1870).—The general procedure of Example I is followed except that 6.2 parts (0.10 mole) of ethanethiol is added to sodium dispersion equivalent to 2.3 parts (0.10 mole) of sodium at an initial temperature of 27° C. and allowing the temperature to rise to 65° C. during the mercaptan addition. The mixture is then heated to reflux and 19.2 parts (0.10 mole) of di-n-butylcarbamyl chloride is added. There is obtained 16.7 parts (76.8% yield) of ethyl N,N-di-n-butylthiocarbamate (B.P. (22 mm.) 154.0-154.5°, n_D^{29} 1.4740).

Example VIII (R-1606).—273 parts of anhydrous isopropanol are added to a glass or steel reactor and 3.5 parts (0.153 mole) of sodium is added. The mixture is heated to reflux and the sodium gradually dissolves. The solution is then rapidly cooled in ice water. At 50° C., a thick solid of sodium isopropoxide comes out of solution. The mixture is cooled to 30° and then 9.17 parts (0.191 mole) of methanethiol is added rapidly. The solid dissolves immediately. The clear solution is heated to boiling and 198 parts of isopropanol is distilled off. 89 parts of anhydrous xylene is then added and 77 parts of isopropanol-xylene mixture is distilled. 89 parts more xylene is added and 89 parts of isopropanol-xylene mixture is distilled. 89 parts more xylene is added and 89 parts of solvent, probably pure xylene by now, is distilled. 49 parts more xylene is added, the mixture is heated to reflux, and 25 parts of di-n-propylcarbamyl chloride is added during 4 minutes. The reaction is not very exothermic. The mixture is then refluxed for 14 hours, cooled, filtered from salt, the cake is washed with a little xylene and the solvent is removed under reduced pressure. The residue is then vacuum distilled and there is obtained 16.7 parts (62.5% yield) of methyl N,N-di-n-propylthiocarbamate (B.P. (30 mm.) 128.5-129.5°, n_D^{26} 1.4808).

Example IX (R-1817).—When the general procedure of Example VIII is repeated except that 11.7 parts (0.188 mole) of ethanethiol, 3.45 parts (0.15 mole) of sodium and 22.1 parts of N,N-pentamethylenecarbamyl chloride are employed, there is obtained 14.4 parts (55.5% yield) of ethyl N,N-pentamethylenethiocarbamate (B.P. (31.5 mm.) 150.5-151.0°, n_D^{25} 1.5168).

Example X (R-1905).—When the general procedure of Example VIII is repeated except that 13.0 parts (0.125 mole) of 1-pentanethiol, 2.3 parts (0.10 mole) of sodium and 16.4 parts of di-isopropylcarbamyl chloride are employed, there is obtained 15.8 parts (68.3%) of n-amyl N,N-di-isopropylthiocarbamate (B.P. (22 mm.) 145-149° C., n_D^{30} 1.4721).

Example XI (R-1824).—When the general procedure of Example VIII is repeated except that 14.3 parts (0.188 mole) of 2-propanethiol, 3.45 parts (0.15 mole) of sodium and 22.1 parts (0.15 mole) of N,N-pentamethylenecarbamyl chloride are employed, there is obtained 12.7 parts (45.2% yield) of isopropyl N,N-pentamethylenethiocarbamate (B.P. (17 mm.) 138.0-138.2°, n_D^{27} 1.5083).

The compounds of the present invention have been extensively tested as herbicides and have been particularly evaluated as pre-emergence herbicides. Pre-emergence herbicides are ordinarily used by placing a narrow band of the herbicide over the center of a seeded crop row at time of planting or before crop emerges. If the herbicide is harmless to the desired crop, seeds or seedlings, but phytotoxic to the weed seeds or seedlings most frequently encountered, the crop grows in an almost weed-free environment. Of course, the pre-emergence herbicide may be used over the entire field, but it is normally used in a narrow band which straddles the crop row and the balance of the weeds are controlled by various cultivation methods. The herbicides of the present invention are selective toward small seeded annual grasses and broad-leaved plants, and so are effective against the most common weeds but have little effect on such valuable row crops as corn and beans. The phytocidal composition may be applied to the soil in any convenient form. For instance, it can be dissolved in a solvent, such as acetone, or emulsified and sprayed onto the soil, or it can be combined with a dry inert carrier and applied as a dust or as granules; although the composition may be applied to an entire crop plot, it is generally preferred to apply it in a narrow band, say 6", over the seeded row of a newly planted crop. Generally, rates of application of from one-half to twenty pounds per acre of actual area treated will be found suitable.

The following example shows the effect of R-1608 when used to protect corn from weeds:

Example XII.—A field test consisted of applying the compounds at the rate of 1, 2, 4, 8 and 10 pounds/80 gallons/acre as pre-emergence treatments to corn. The compound was dissolved in a small amount of acetone emulsified in water and applied at the desired rate by mounting a spray nozzle behind the planter packer wheel. A 6" band was applied and the rates of application are on the basis of the area of actual application and not on the total area of the plot treated. The weather was sunny, the air temperature 70° F., the soil temperature was 78°, and the seed bed was in good tilth and very dry. Immediately after the test, the plots were sprinkler irrigated. Each treatment was replicated three times. Before the test the entire area had been seeded with rye and oats. Dead nettle seeds were present in the soil. In each case, the growth of the corn was normal in comparison with check plots. The following data were obtained:

Example XIII.—A number of the compounds were tested at rates of application of 80 and 20 pounds per acre. The method of testing was to plant the seeds in 3" diameter paper cans and drench the material on at 30 ml./can. The seeds tested were peas, corn, radish, cucum-

ber and either rye or oats. The data set forth in Table 2 were obtained:

Ge. = Percentage of seeds germinating.

Gr. = Growth wherein 10 equals normal growth, and 0 indicates no growth.

We claim:

1. As a composition of matter, a compound of the formula

wherein R_1 is a lower alkyl radical and R_2 and R_3 are identical lower alkyl radicals having at least three carbon atoms.

2. As a composition of matter ethyl N,N-di-n-propylthiolcarbamate.

3. As a composition of matter ethyl N,N-di-n-butylthiolcarbamate.

ing to the soil a phytotoxic amount of a compound having the formula

wherein R_1 is a lower alkyl radical and R_2 and R_3 are identical lower alkyl radicals having at least three carbon atoms.

8. The process of claim 7 wherein the compound is applied in a narrow band to a row crop at a rate of application of from one-half to twenty pounds per acre of area actually treated.

9. The method of combatting weeds comprising apply-

ing to the soil a phytotoxic amount of ethyl N,N-di-n-propylthiolcarbamate.

10. The method of combatting weeds comprising applying to the soil a phytotoxic amount of ethyl N,N-di-n-butylthiolcarbamate.

11. The method of combatting weeds comprising applying to the soil a phytotoxic amount of n-propyl N,N-di-n-propylthiolcarbamate.

12. The method of combatting weeds comprising applying to the soil a phytotoxic amount of n-propyl N,N-di-n-butylthiolcarbamate.

13. The method of combatting weeds comprising applying to the soil a phytotoxic amount of n-amyl N,N-di-isopropylthiolcarbamate.
